UNITED STATES PATENT OFFICE.

HORACE RAINES, OF FORT BRANCH, INDIANA.

COAL-TIPPLE.

1,378,276.

Specification of Letters Patent. Patented May 17, 1921.

Application filed July 26, 1920. Serial No. 398,982.

To all whom it may concern:

Be it known that I, HORACE RAINES, a citizen of the United States, residing at Fort Branch, in the county of Gibson and 5 State of Indiana, have invented new and useful Improvements in Coal-Tipples, of which the following is a specification.

The invention relates to hoisting apparatus, being particularly adapted for the 10 handling of coal in the loading and unloading thereof.

The invention appertains to coal tipples wherein two cars or platforms are connected by means of a cable so that one acts as a 15 counter-balance for the other, and wherein the hoisting cables are reversely wound on the operating drum to cause one car to ascend while the other descends and vice versa.

20 The invention provides a novel framing and arrangement of hoisting tackle, all as will appear more fully hereinafter, reference being had to the accompanying drawings in which,

25 Figure 1 is an elevation of a coal tipple embodying the invention.

Fig. 2 is a horizontal section on the line 2—2 of Fig. 1 showing the parts on a larger scale.

30 Fig. 3 is a detail vertical section on the line 3—3 of Fig. 1 looking in the direction of the arrow and showing the parts on a larger scale.

35 Corresponding and like parts are referred to in the following description and indicated in the several views of the drawings by like reference characters.

The drawings illustrate a preferred embodiment of the invention. However, it is 40 to be understood that in adapting the same to meet specific requirements and conditions various changes in the form, proportion and minor details of construction may be resorted to without departing from the nature 45 of the invention as claimed.

The tipple or apparatus illustrated embodies a framing upon which is mounted two cars or platforms 1 and 2 which are adapted to move vertically in suitable shafts and 50 which are directed in their vertical movements by means of bars 3 which constitute parts of the framing. The shafts 4 and 5 are disposed in close relation and may be of any substantial structure and are provided 55 at the top with a series of pulleys 6, 7 and 8 which give direction to the operating tackle

such as the cables. The cars or platforms 1 and 2 are connected by means of a cable 9 which passes over the topmost pulley 6. It will thus be understood that one car or platform acts as a counterbalance for the other. The pulley 6 is of such diameter that its opposite portions are in line with the vertical elements or parts of the cable 9. The several pulleys are grooved in their outer 60 edges to provide seats to retain the respective cables in proper position against accidental lateral displacement. The pulleys 7 and 8 are disposed in a lower plane than the pulley 6 and are located so as to engage 65 the respective end portions of the cable 9 which engage the grooves thereof to retain the several cables in proper position. The pulley 8 is arranged wholly to the right of the right hand vertical portion of the cable 70 9 so that the inner grooved edge of the pulley 8 receives the right hand end portion of the cable 9. The pulley 7 is likewise disposed wholly to the right of the left hand end portion of the cable 9 so that its outer grooved 75 edge will receive the left hand end portion 80 of the cable 9.

The winding or hoisting drum 10 may be conveniently disposed and adapted to be operated in any preferred way. The hoisting cable 11 passing over the pulley 8 is connected to the car or platform 2 and is adapted to wind upon the drum 10 in a clockwise direction. The cable 12 passing over the pulley 7 is connected to the car or platform 1 and is adapted to wind upon the drum 10 in a counterclockwise direction. It will thus be understood that the cables 11 and 12 are 85 reversely wound upon the operating drum 10 so that as one of the cars or platforms 90 ascends the other descends and vice versa. The vertical portions of the several cables are in close relation so as to engage the grooved edges of the respective pulleys 7 and 8. As means for operating the hoisting 95 drum 10 a shaft 13 is provided. A crank 14 is applied to one end of the shaft 13 and suitable gearing 15 connects the shaft 13 with the drum whereby provision is had for 100 manual operation of the hoisting drum. 105

The cars or platforms are of like construction, each embodying a platform, uprights 16, cross bars 17 connecting corresponding uprights and cross beams 18 connecting companion cross bars. Each of the 110 cross beams 18 is provided at a middle point with a short cross bar 19 to which is fitted

a clevis 20 having a centrally disposed eye 21. A similar clevis 22 is attached at its ends to each of the cross beams 18 and is provided centrally with an eye 23 which is 5 interlooped with the eye 21. In this manner the clevises 20 and 22 mutually brace each other. The respective cables are connected with the interlooped eyes to the clevises thereby resulting in a substantial and firm 10 connection. In the operation of the invention the parts when assembled occupy the relative position substantially as shown in the drawings. One of the cars or platforms acts as a counter-balance for the other. By 15 having the hoisting cables 11 and 12 reversely wound upon the hoisting drum 10 a minimum amount of power is required to be expended for operating the cars because of the counter-balancing action of one upon 20 the other. The power required to be expended is such as to overcome inertia of the parts and move the excess of load as will be readily understood. The end portions of the cable 9 are given positive direction be- 25 cause of their engagement with the respective pulleys 7 and 8 whereby lateral displacement of the cable from the pulley 6 is guarded against.

What I claim is:

- 30 1. In hoisting apparatus of the character specified, a supporting frame-work including shafts, cars mounted in the shafts for vertical movement, a cable connecting the cars whereby one of the cars acts as a counter-balance for the other car, a hoisting drum, hoisting cables reversely wound upon the hoisting drum and connected with the respective cars, a guide pulley for the cable connecting the cars and other guide pulleys 35 disposed in a lower plane than the first mentioned guide pulley and receiving the hoisting cables and disposed to engage the vertical end portions of the cable connecting the cars.

2. In hoisting apparatus, a car embodying 45 a cross beam and a central cross bar, a clevis having its end portions engaging the ends of the cross bar and provided centrally with an eye and a second clevis having its end portions engaging the cross beam and 50 provided centrally with an eye interlooped with the eye of the first mentioned clevis, the interlooping eyes being adapted to receive the hoisting cable.

3. Hoisting apparatus of the character 55 specified, embodying a framing including vertical shafts, cars mounted in the shafts for vertical movement, a cable connecting the cars to admit of one car forming a counter-balance for the other car, hoisting cables 60 connected with the respective cars, a hoisting drum having the hoisting cables reversely wound thereon, a guide pulley of a diameter corresponding with the distance between the centers of the shafts and receiving 65 the cable connecting the cars and grooved pulleys disposed in a plane below the beforementioned pulley and receiving the hoisting cables and the respective vertical end portions of the cable forming connecting means between the two cars. 70

4. Hoisting apparatus of the character 75 specified, including a pair of shafts, a car mounted to travel in each of the shafts, a guide pulley of a diameter corresponding with the distance between the centers of the shafts, a cable running freely over the pulley, and connected at opposite ends to the cars which are suspended upon the cable and counter-balance one another, a hoisting pulley for each car, each hoisting pulley being disposed below and in the same plane with the guide pulley, hoisting cables engaging 80 the respective guide pulleys and connected to the respective cars, and a hoisting drum 85 having the hoisting cables reversely wound thereon.

HORACE RAINNEY.
